REFLECTOR FOR LIGHTING FIXTURES

Fred M. Gore, Dallas, Tex., and Alois J. Koller, Fenton,
Mo., assignors to The Cuffman Company, Inc., Mal-
vern, Ark., a corporation of Arkansas

Filed Aug. 15, 1961, Ser. No. 66,353

Term of patent 14 years

(Cl. D48—16)

FIG.1

FIG.4

FIG.2

FIG.5

FIG.3

FIG 6

FIG 9

FIG 7

FIG 10

FIG 8

FIGURE 1 is a perspective view of a reflector for lighting fixtures showing our new design;

FIGURE 2 is front elevation thereof as shown in FIGURE 1;

FIGURES 3 and 4 are respectively top and bottom plan views thereof as shown in FIGURE 1;

FIGURE 5 is a side elevation thereof as shown in FIGURE 1;

FIGURE 6 is a modified form of the reflector for lighting fixture shown in FIGURE 1;

FIGURE 7 is a front elevation thereof as shown in FIGURE 6;

FIGURES 8 and 9 are respectively top and bottom plan views thereof as shown in FIGURE 6;

FIGURE 10 is a side elevation thereof as shown in FIGURE 6.

We claim:

The ornamental design for a reflector for lighting fixtures, as shown and described.
